UNITED STATES PATENT OFFICE.

BYARD F. BROGAN, OF PHILADELPHIA, PENNSYLVANIA.

DESIGN FOR A FINGER RING.

Application filed August 15, 1923. Serial No. 7,018. Term of patent 3½ years.

To all whom it may concern:

Be it known that I, BYARD F. BROGAN, a citizen of the United States, residing at Philadelphia, in the county of Philadelphia and State of Pennsylvania, have invented a new, original, and ornamental Design for Finger Rings, of which the following is a specification, reference being had to the accompanying drawing, forming part thereof.

I claim:

The ornamental design for a finger ring, as shown.

BYARD F. BROGAN.
